UNITED STATES PATENT OFFICE.

ARTHUR M. HOOD, OF INDIANAPOLIS, INDIANA.

EXCAVATOR.

Application filed December 27, 1923. Serial No. 682,920.

To all whom it may concern:

Be it known that I, ARTHUR M. HOOD, a citizen of the United States, residing at Indianapolis, in the county of Marion and State of Indiana, have invented a new and useful Excavator, of which the following is a specification.

The object of my invention is to provide certain improvements in construction of a scraper bucket type of excavator, commonly known as a slack line excavator, by means of which material may be excavated at one point and dumped at another. The accompanying drawings illustrate my invention.

Fig. 1 is a side elevation of an embodiment of my invention; Fig. 2 a plan; Fig. 3 a fragmentary vertical section with the parts in the positions immediately preceding gravity dumping action; Fig. 4 a fragmentary section on line 4—4 of Fig. 1; Fig. 5 a front elevation of the carriage and immediately associated parts, and Fig. 6 a side elevation of another embodiment of my invention.

In the drawings 10 indicates a track cable upon which the apparatus is most conveniently mounted and operated, said track cable being generally arranged with its lower end attached to a "dead man" and its upper end attached to a suitable block and tackle by which the track cable may be conveniently slackened and tautened, this construction being common and well-known in the art.

Movably mounted upon and along the track cable is a carriage 11 from which is suspended, by means of the suspension member 12, a forwardly unbalanced scraper bucket 13.

Located in the lower forward portion of carriage 11 is a double idler 14 composed of two slightly spaced portions each having a chain supporting peripheral portion 14', the two parts being so arranged that the lifting chain 15 may ride thereon, without entering the space 16 between the two portions of idler 14, to normally support the forwardly unbalanced weight of bucket 13.

As a part of chain 15 I provide a long link 17 the thickness of which is such as to permit its entry into the space 16, the points of attachment 17' and 17' between the upper and lower portions of chain 15, respectively, and link 17, being so proportioned that, when the parts are drawn to the position shown in Fig. 1, the point of attach-

ment 17' will be at the periphery 14', line 17 will lie within space 16, and the point of attachment 17" effectively nearer the axis of idler 14 than is the point of attachment 17'. Preferably these proportions are such that the point 17' will be in advance of the vertical plane of the axis of idler 14 and the point of attachment 17" will be either directly beneath or slightly in advance thereof, in which latter case the unbalanced weight of the bucket and its load will have no tendency to move the link 17 rearwardly.

The upper end of link 17, when in the position shown in Fig. 1, lies in the path of movement of the lower end of a lever 18 pivoted at 19 on carriage 11, the upper end of this lever lying between a pair of fingers 20—20 on a latch bar 21, having a pin and slot connection 22 with carriage 11.

The latch bar 21 is projected somewhat in advance of carriage 11 and at its forward end is so formed as to have a latching cooperation with a block, or other catch, 23, secured to the cable at the desired dumping point.

In order to automatically release latch 21 from block 23, any one of a number of constructions may be adopted. For instance, the rear end of latch 21 may be provided with an arm 25 extended rearwardly beyond the pivotal connection 22, and to this extension may be attached a chain 26, the lower end of which is attached to bucket 13, the length of the chain 26 being such that when the bucket has been allowed to swing, under the action of gravity, so as to dump its load, chain 26 will be taut, and latch 21 automatically released from block 23. Instead of extension 25 and chain 26, block 23 may be provided with a bell crank lever 30 operated by a pull line 31 extending from the operating station, or latch 21 may be provided with a cross bar 32 which by a forward movement of the carriage may be brought into engagement with the tapered rear end of block 23.

Movement of carriage 11 along the track cable is controlled by a dragline 35 which at 36 is bifurcated and extended to the forward end of the bucket, and a movement of carriage 11 along the track cable, is controlled by a dragline.

The lift line 15 is connected to the dragline, conveniently at bifurcation 36, the parts being so proportioned that, when a transporting forward pull is exerted upon

the dragline 35, the parts will be drawn to the position shown in full lines where the link 17, lying in the space 16, will largely decrease, or, preferably, temporarily wholly 5 eliminate, the efficiency of the unbalanced weight tending to cause a rearward movement of the lift line 15 and a consequent dumping of the load.

The operation is as follows: The parts 10 have been brought to the position shown in Fig. 1 by a forward pull on the dragline 35, latch 21 having ridden over block 23 and dropped into latching engagement therewith. Upon a release of drag upon the 15 dragline, the upper forward end of chain 15 will be slackened and the dragline, relative to the bucket, will also be slackened.

Thereupon, the carriage 11 will move by gravity rearwardly on the track cable and, 20 by reason of the pin and slot connection 22, there will be a slight relative movement longitudinally of the carriage between the latch bar and the carriage, so that lever 18 will be swung so as to kick the link 17 rearwardly and thus carry the point of attachment 17' back to a point where the unbalanced weight of the bucket and its load 25 may become effective to draw the chain 15 rearwardly and downwardly, and thus permit the bucket, by reason of its forwardly unbalanced weight, to swing its forward end downwardly and thus dump its load.

If chain 26 is utilized, the latch 21 will be automatically withdrawn from block 35 at the end of the downward swing of the bucket and the carriage will thus be free to slide downwardly along the track cable. The track cable will then be slackened so as to permit the bucket to descend to the point 40 of excavation, whereupon a forward pull on the dragline will draw the bucket forwardly and at the same time will draw link 17 into the position shown in Fig. 1. The bucket being filled, the track cable is tautened and the parts drawn into the position 45 shown in Fig. 1, and the operation repeated.

If instead of the chain 26, the bell crank 30 is used, the operator will, when the load 50 has been dumped, pull upon cable 31 to cause a release of the latch bar 21, and the further operation will be as described above.

If, instead of the chain 26, or bell crank 30, the cross bar 32 is used, the operator 55 will, after a load has been dumped, exert a forward pull upon the dragline, so as to return bucket and link 17 to the position shown in Fig. 1 and will continue this forward pull until cross bar 32 engages block 60 23 whereupon by a sudden release of pull upon the dragline, the carriage will move backwardly before the latch can drop in front of block 23 and the carriage and its bucket will descend to the excavating position.

If link 17 is formed in the preferred manner described above, the bucket will remain in its upper position as the carriage descends, but in any event, a forward pull upon the dragline, from the excavating 70 point, serves to restore link 17 to its position between the idlers 14.

The advantage of line 17 and its co-operation with idler 14 resides in the fact that if the chain 15 should be passed over an ordinary idler the bucket could only be maintained in load-carrying position by a substantially uniform maintenance of forward pull upon the dragline, and practically this is not possible, because of variations of speed of the carriage and because of vertical vibrations in the slack line track cable, whereas the co-operation of link 17 with the special idler 14 is such that the effect of the forwardly unbalanced load on chain 15 is either materially reduced, or, preferably, entirely eliminated.

In Fig. 6 the means for increasing the bucket-dumping effectiveness of the forwardly unbalanced bucket weight is operated by a forward inertia movement of the carriage on its track following a discontinuance of pull on the dragline.

In this form I provide a plunger 40 slidably mounted on carriage 11 and arranged to bump into stop block 41 and be thus driven against link 17 so as to kick it rearwardly. This specific construction forms the subject matter of a companion application.

I claim as my invention:

1. An excavator of the type described, comprising a carriage, a forwardly unbalanced scraper bucket pivotally supported on said carriage, a dragline connected to the forward end of the bucket, a lifting line connected to the forward end of the bucket and passed over a support on the carriage to the dragline, means for decreasing the bucket-dumping effectiveness of the forwardly unbalanced weight of the bucket, a latch carried by the carriage and adapted to at times limit reverse movement of the carriage, and means operated by relative longitudinal movement between the carriage and latch for increasing the bucket-dumping effectiveness of the forwardly unbalanced weight of the bucket.

2. An excavator of the type described, comprising a carriage, a forwardly unbalanced scraper bucket pivotally supported on said carriage, a dragline connected to the forward end of the bucket, a lifting line connected to the forward end of the bucket and passed over a support on the carriage to the dragline, means for decreasing the bucket-dumping effectiveness of the forwardly unbalanced weight of the bucket, a latch carried by the carriage and adapted to at times limit reverse movement of the carriage,

means operated by relative longitudinal movement between the carriage and latch for increasing the bucket-dumping effectiveness of the forwardly unbalanced weight of the bucket, and means for withdrawing the latch from carriage-restraining position. 5

3. An excavator of the type described, comprising a carriage, a forwardly unbalanced scraper bucket pivotally supported on said carriage, a dragline connected to the forward end of the bucket, a lifting line connected to the forward end of the bucket and passed over a support on the carriage to the dragline, means for decreasing the bucket-dumping effectiveness of the forwardly unbalanced weight of the bucket, and means movably mounted on the carriage and adapted to co-operate with a carriage-support for increasing the 10 bucket-dumping effectiveness of the forwardly unbalanced weight of the bucket. 15

4. An excavator of the type described comprising a carriage, a forwardly unbalanced scraper bucket, pivotally supported on said carriage, a dragline connected to the forward end of said bucket, a lifting line connected to said dragline and extended back over a support on the carriage and thence downwardly to the forward end of the bucket, the said lifting line and its carriage-support being of such character that, when the lifting line has lifted the bucket to load-carrying position, the effectiveness of the unbalanced weight of the bucket tending to cause rearward movement of the lifting line is less than it is just before the bucket reaches load-carrying position, and means movably mounted on the carriage and adapted to cooperate with a carriage-support for increasing the bucket-dumping effectiveness of the forwardly unbalanced weight of the bucket. 20

5. An excavator of the type described comprising a carriage, a forwardly unbalanced scraper bucket, pivotally supported on said carriage, a dragline connected to the forward end of said bucket, a lifting line connected to said dragline and extended back over a support on the carriage and thence downwardly to the forward end of the bucket, the said lifting line and its carriage-support being of such character that, when the lifting line has lifted the bucket to load-carrying position, the effectiveness of the unbalanced weight of the bucket tending to cause rearward movement of the lifting line is less than it is just before the bucket reaches load-carrying position, a latch carried by the carriage and adapted to at times limit reverse movement 25 of the carriage, and means operated by relative longitudinal movement between the carriage and latch for increasing bucket-dumping effectiveness of the forwardly unbalanced weight of the bucket. 30

6. An excavator of the type described comprising, a carriage, a forwardly unbalanced scraper bucket pivotally supported on said carriage, a dragline connected to the forward end of the bucket, a lifting chain connected to the dragline and extended back over a support on the carriage and thence downwardly to the forward end of the bucket, the said lifting chain comprising a link 35 and the support formed to permit the link to move to a position closer to the axis of the support than is permitted the adjacent advance portion of the chain, and means other than the bucket for positively shifting said link rearwardly relative to its carriage support. 40

7. An excavator of the type described comprising, a carriage, a forwardly unbalanced scraper bucket pivotally supported on said carriage, a dragline connected to the forward end of the bucket, a lifting chain connected to the dragline and extended back over a support on the carriage and thence downwardly to the forward end of the bucket, said chain comprising a link 45 and the support formed to permit the link to move to a position closer to the axis of the support than is permitted the adjacent advance portion of the chain, and means other than the bucket for positively shifting said link rearwardly relative to its carriage support. 50

8. An excavator of the type described comprising, a carriage, a forwardly unbalanced scraper bucket pivotally supported on said carriage, a dragline connected to the forward end of the bucket, a lifting chain connected to the dragline and extended back over a support on the carriage and thence downwardly to the forward end of the bucket, said chain comprising a link 55 and the support formed to permit the link to move to a position closer to the axis of the support than is permitted the adjacent advance portion of the chain, and means other than the bucket and controlled by movement of the carriage on its support, for shifting said link rearwardly relative to its carriage support. 60

9. An excavator of the type described comprising, a carriage, a forwardly unbalanced scraper bucket pivotally supported on said carriage, a dragline connected to the forward end of the bucket, a lifting chain connected to the dragline and extended back over a support on the carriage and 65

10. An excavator of the type described comprising, a carriage, a forwardly unbalanced scraper bucket pivotally supported on said carriage, a dragline connected to the forward end of the bucket, a lifting chain connected to the dragline and extended back over a support on the carriage and 70

11. An excavator of the type described comprising, a carriage, a forwardly unbalanced scraper bucket pivotally supported on said carriage, a dragline connected to the forward end of the bucket, a lifting chain connected to the dragline and extended back over a support on the carriage and 75

12. An excavator of the type described comprising, a carriage, a forwardly unbalanced scraper bucket pivotally supported on said carriage, a dragline connected to the forward end of the bucket, a lifting chain connected to the dragline and extended back over a support on the carriage and 80

13. An excavator of the type described comprising, a carriage, a forwardly unbalanced scraper bucket pivotally supported on said carriage, a dragline connected to the forward end of the bucket, a lifting chain connected to the dragline and extended back over a support on the carriage and 85

14. An excavator of the type described comprising, a carriage, a forwardly unbalanced scraper bucket pivotally supported on said carriage, a dragline connected to the forward end of the bucket, a lifting chain connected to the dragline and extended back over a support on the carriage and 90

15. An excavator of the type described comprising, a carriage, a forwardly unbalanced scraper bucket pivotally supported on said carriage, a dragline connected to the forward end of the bucket, a lifting chain connected to the dragline and extended back over a support on the carriage and 95

16. An excavator of the type described comprising, a carriage, a forwardly unbalanced scraper bucket pivotally supported on said carriage, a dragline connected to the forward end of the bucket, a lifting chain connected to the dragline and extended back over a support on the carriage and 100

17. An excavator of the type described comprising, a carriage, a forwardly unbalanced scraper bucket pivotally supported on said carriage, a dragline connected to the forward end of the bucket, a lifting chain connected to the dragline and extended back over a support on the carriage and 105

18. An excavator of the type described comprising, a carriage, a forwardly unbalanced scraper bucket pivotally supported on said carriage, a dragline connected to the forward end of the bucket, a lifting chain connected to the dragline and extended back over a support on the carriage and 110

19. An excavator of the type described comprising, a carriage, a forwardly unbalanced scraper bucket pivotally supported on said carriage, a dragline connected to the forward end of the bucket, a lifting chain connected to the dragline and extended back over a support on the carriage and 115

20. An excavator of the type described comprising, a carriage, a forwardly unbalanced scraper bucket pivotally supported on said carriage, a dragline connected to the forward end of the bucket, a lifting chain connected to the dragline and extended back over a support on the carriage and 120

21. An excavator of the type described comprising, a carriage, a forwardly unbalanced scraper bucket pivotally supported on said carriage, a dragline connected to the forward end of the bucket, a lifting chain connected to the dragline and extended back over a support on the carriage and 125

22. An excavator of the type described comprising, a carriage, a forwardly unbalanced scraper bucket pivotally supported on said carriage, a dragline connected to the forward end of the bucket, a lifting chain connected to the dragline and extended back over a support on the carriage and 130

thence downwardly to the forward end of the bucket, said chain comprising a link 17 and the support formed to permit the link to move to a position closer to the axis of the support than is permitted the adjacent advance portion of the chain, a latch carried by the carriage and adapted to at times

limit rearward movement of the carriage, and means acting on the link 17 and controlled by rearward movement of the carriage relative to the latch shifting said link rearwardly relative to its carriage support. ¹⁰

ARTHUR M. HOOD.
